UNITED STATES PATENT OFFICE.

ENOS S. HAWKS, OF CUMMINGTON, MASSACHUSETTS.

PAINTING-MACHINE.

SPECIFICATION forming part of Letters Patent No. 443,576, dated December 30, 1890.

Application filed October 8, 1888. Serial No. 287,570. (No model.)

To all whom it may concern:

Be it known that I, ENOS S. HAWKS, a citizen of the United States of America, residing at Cummington, in the county of Hampshire and State of Massachusetts, have invented 5 certain new and useful Improvements in Painting-Machines; and I do hereby declare the following to be a full, clear, and exact description of the invention, such as will enable others skilled in the art to which it appertains 10 to make and use the same, reference being had to the accompanying drawings, and to letters and figures of reference marked thereon, which form a part of this specification.

15 This invention relates to painting-machines designed to paint plain surfaces, such as the sides of houses; and it consists in the improved construction, hereinafter set forth and claimed.

20 In the accompanying drawings, Figure 1 is a front view of a painting-machine constructed in accordance with my invention. Fig. 2 is a rear view. Fig. 3 is a vertical section taken through the line $x-x$ of Fig. 1, partly broken 25 away at the top. Fig. 4 is a front view of a portion of the operating mechanism, the parts being broken away. Fig. 5 is a detail perspective view. Fig. 6 is a front view of one 30 of the intermittent gear-wheels. Fig. 7 is a front view of the bar upon which the wheel in Fig. 6 is mounted. Fig. 8 is a plan view of the intermittent wheel mounted above the wheel shown in Fig. 6. Fig. 9 is a sectional view of the brush-carriage, looking from the 35 under side thereof. Fig. 10 is a detail plan view of the brush-carriage. Fig. 11 is a sectional view through the dotted line $w-w$ of Fig. 1, taken through the brush-carriage and adjacent parts. Fig. 12 is a sectional view 40 through the dotted line $y-y$ of Fig. 1. Fig. 13 is a sectional view through the dotted line $z-z$ of Fig. 1.

The main frame of the machine has vertical posts A, Figs. 1, 2, 3, 4, and 12, to which 45 are secured, so as to be adjustable thereon, cross-beams A', to which are movably attached clamps a , each having portions bent to embrace the beams, the free ends of said 50 portions being adjacently arranged and perforated for the engagement of a bolt a' to secure the clamp on the beam. Each clamp

is extended at its rear to form a projection a^2 , the inner side of which may be roughened or padded to bear against the sides of the building at right angles and thus enable the 55 main frame to be rigidly clamped on the front of the building by devices now described.

Transversely through the rear extended portions of the upper and lower clamps passes a horizontal rod a^3 , Figs. 2 and 3, one end of 60 which is shouldered to bear against the outer side of the adjacent clamp, while the other end portion beyond the clamp nearest thereto is screw-threaded for the engagement of a thumb-nut a^5 , enabling each upper and lower 65 pair of clamps to positively engage the corner portions of the building.

Through the depending portions of the clamps a passes a screw-threaded crank-shaft a^4 , Figs. 1, 2, and 3, the end of which is 70 adapted to abut against the front of the building, adjacent to the corners thereof, to steady and prevent the vibration of the main frame and insure the proper contact of the brushes with the surface of the building. 75

At the intersection of the posts A and beams A' clamps B B, Figs. 1, 2, 3, and 4, are located, these clamps consisting of plates b and b' , which are connected to each other rigidly by posts b^2 , riveted to the rear plates. 80 Upon these posts, which are four in number, a disk b^3 , (shown in Fig. 3,) having corresponding perforations, is placed, and with the center of said disks a set-screw B^4 engages, the plate b' being screw-threaded, so that said 85 set-screw will engage therewith and the end thereof bear upon the movable disk b^3 , so as to hold the parts securely in position. It will be observed that the main frame can be extended laterally and vertically, so as to be 90 placed upon buildings of different widths and heights.

Each post A is provided on its inner and outer side with a vertical longitudinal groove A². A transverse brush-carrying frame is 95 composed of horizontal beams C C, which are secured in position by means of vertical bars c^5 , playing in the inner and outer grooves, each pair of bars carrying adjacent to the upper and lower beams C C four rearwardly-extending horizontal bolts, in which the beam is seated, said beam being retained in posi- 100

tion by a back plate c , which embraces the ends of the several bolts at each intersection. The upper and lower plates c at one side may be connected rigidly to the horizontal beams; but at the opposite side they are removably connected by means of screws c' to admit of the parts being loosened and provide for a lateral adjustment of the clamping means proportionate with the movement of the post A of the main frame, when the width of the latter is to be adjusted. The upper beam C is provided on its rear side with a rack-bar C' , with which a wheel for operating the brushes engages, as will be hereinafter set forth. These beams C are provided on their opposite horizontal faces with grooves c^2 , as seen in Fig. 3, in which the brush-carriage moves and is guided. One of the upper clamps c is provided with a bearing c^4 , Fig. 2, through which a spirally-grooved shaft S passes, the opposite end of said shaft being supported by a bracket secured near one end of the upper beam C . From the upper portions of the outer bars C extend brackets c^6 , Fig. 1, which are internally screw-threaded, and through the same the vertical screw-threaded shafts D pass, the front disks b' of the upper clamps B having brackets b^6 and b^7 , Figs. 1 and 2, secured thereto, these brackets having horizontal bent portions, which serve as bearings for vertical shafts, as shown, said shafts turning freely in said bearings. D , Figs. 1, 2, and 3, refer to screw-threaded shafts, which are mounted in bearings, so as to be maintained in a position parallel with the posts A of the main frame, the lower portion of these screw-threaded shafts being mounted in bearings attached to projecting arms d and d' , which are rigidly attached to the posts A . The lower ends of these shafts have attached thereto beveled gear-wheels which engage with beveled wheels mounted on a horizontal shaft E , so that the brush-carrying frame will be raised or lowered when the screw-threaded shafts D are turned. The said shaft E is provided with a longitudinal groove e , and is supported in suitable bearings connected to the posts A . This shaft carries beveled pinions 1, 2, 3, and 4, said beveled pinions being adapted to mesh in corresponding pinions d^2 and f on the lower ends of the several shafts D . The pinions 1 and 2 are loosely mounted on the shaft E and are thrown in connection with said shaft by clutches g and g' , carried by suitable arms connected to a bar G . The arm carrying the clutch g is adjustably secured to the bar G , while the arm carrying the clutch g' is rigidly secured thereto. One end of the shaft E has secured thereto a crank arm or pulley for turning the same, and by this shaft the machine is operated.

The shaft E , in addition to carrying the pinions heretofore referred to, also carries a worm E' , which has pivoted thereto a dog e^2 , adapted to fold down to lie partially within

the groove e , Fig. 4, and when placed within said groove it is held in position by a spring-clamp attached to the dog, which will hold the same in place against displacement. 70

The bars G , Figs. 1 and 2, may be made of a single piece having an outwardly-bent portion, or a bent portion may be attached thereto, so as to allow the gear-wheels to lie above the same. The end of this bar is connected to a plate H by a bolt which passes through a slot formed therein, and at its end it is provided with a spring g^2 , which engages with a stud h , projecting from the plate H , Figs. 1 and 4. This bar G is thrown to the right and left by a lever i , pivoted to the plate H , and connected by a link i' to the bar G , so that by moving said lever the clutches carried by said bar will be thrown either in or out of engagement with the pinions mounted on the grooved shaft E . The bar G also carries a dog I , adapted to engage an outward projection n^2 , formed on a gear-wheel N , to throw said bar automatically, the action of which will be hereinafter set forth. It will be observed 90 that the bar G is attached movably to one of the posts, so that the post can be extended laterally.

The plate H , Figs. 1, 2, 4, and 7, is secured rigidly to the post A of the main frame, and also to the end of the lower cross-beam A' thereof, and it is provided with an outwardly-projecting stud h^4 , against which bears a bar K , (shown in detail in Fig. 5,) and with this stud h^4 a suitable bolt engages, which passes 100 through the slot in the bar K . This bar K carries arms which engage with clutches h^7 and h^8 , which slide upon the slotted shaft E when the arms are moved, so as to be thrown in or out of engagement with the pinions 3 and 4 upon said shaft. The opposite end of this bar K has a longitudinal slot k^2 , through which passes a bolt k^6 , bearing in the screw upon which cam o' is mounted, and said bolt k^6 supports the other end of said bar. Up to 110 this point of the description with reference to bar K , it will be noted that the two bolts passing through the slots of said bar support it, but enable it to have a transverse horizontal movement. The said bar K is provided on its rear face at either side of the slot k^2 with upper and lower projections k^3 k^4 . A curved spring O^2 , parallel with the periphery of the cam, between the shoulders thereof, has one end secured to said periphery by being seated in a recess therefor in the face of said cam, while the free end of said spring is limited by a pin o^2 projecting from the wheel O . The parts being in the position shown in dotted and full lines, Fig. 4, as the cam revolves in the direction of the arrow the spring will be compressed against the periphery of the cam between the shoulders thereof by the projection k^3 , since the bar K is held immovable by the cam-shoulder bearing against 120 one of the projections while the spring is pressed against the periphery by the other

- projection. Now when the cam-shoulder in contact with the projection k^4 clears the same the relaxing force of the compressed spring, acting on the projection k^3 , will horizontally move said bar K on its bolts, and the further revolution of the cam brings its spring in contact with the projection k^4 , compresses it, and reverses the movement of the bar K in the manner previously explained. The bar K is also provided with a V-shaped slot k^5 , in which a pin p^2 , attached to a member P', (of a lever to be described,) passes, so that the member will be operated when the bar is moved by the cam.
- To one of the vertical posts A of the main frame, above the longitudinal slotted shaft E, is secured a bracket L, Figs. 1, 2, 4, and 12, which has a depending portion, to which is secured by means of a bolt l a hollow knob l' , the lower portion of which knob is reduced in diameter so as to form a bearing upon which the intermittent gear-wheel M will turn. This knob is provided with an arm m , the end of which is provided with a pin adapted to engage with perforations formed adjacent to the periphery of the wheel M, and the opposite side of this arm is provided with an outwardly-projecting pin m' , which engages with a trip-bar R'. By means of this hollow knob and securing-bolt l the arm can be adjusted to enter different perforations, thereby giving, through the intervention of the trip-bar and other mechanism, the distance of the travel of the carriage carrying the brushes. The gear-wheel M meshes with the worm E', located on the shaft E. The hollow knob l (see Fig. 12) has an interior shoulder against which a spiral spring which encircles the bolt engages, so that said knob may be raised upon the bolt l to adjust the arm m to engage the different perforations in the wheel. This spring also serves to hold the wheel M against the depending portion of the bracket L, to prevent the same slipping.
- To the plate H is secured rigidly a disk n , (see Figs. 7 and 13,) over which a gear-wheel N, Fig. 6, is placed. The front face of this gear-wheel has rigidly secured thereto an outwardly-projecting stud or block n' , located between that portion of the wheel from which the teeth are absent, and almost at right angles therewith from the center of the wheel is secured, but nearer the periphery of the wheel, the projecting portion n^2 , which is curved, one end tapering, as fully shown in Fig. 6. The disk n has a raised portion n^3 formed thereon, the height of said portion being substantially the same as the height of the raised projection n' and n^2 of the wheel N.
- Above the portion n^3 is secured, by means of a shouldered bolt, a gear-wheel O, so as to turn upon said bolt, and the rear face of this wheel O has projecting studs o and o' placed at equal distance from the center of said wheel, so that they alternately engage with the stud or projection n' on the toothed wheel N. The outer edge of the gear-wheels N and

O are on a line with each other, so that they will both mesh with the worm E'. The cam O' being rigidly secured to the wheel O, moves therewith, and with the faces of said cam the projections k^3 and k^4 engage to reciprocate or move laterally the bar K.

To the rear side of the plate H is secured a lever or dog P, Figs. 2 and 3, which is pivotally secured to said plate by a pivot-bolt p . The normal vertical portion of this lever carries at its upper end a gravity or spring-actuated pawl p' , which is adapted to engage with the toothed wheel M and advance said wheel forward one tooth. The member P' before referred to, of the lever is substantially at right angles with the vertical portion and carries near its outer end a projecting pin p^2 , which passes through an opening in the plate H and engages with the V-shaped slot k^5 in the bar K, so that when said bar is thrown by the rotation of the cam O' the upper end, which carries the pawl, will be thrown or moved so as to advance the wheel M. This lever P is provided with a spring p^3 for reTRACTING the same and maintaining it in position.

To the rear side of the plate H is also secured a lever R, comprising members R' and R^2 . This lever R is pivoted to the rear of the plate H by a bolt, and the member R' extends upwardly, and near its end is bent to engage with the projecting stud m' , formed on the arm m , by which it is operated or thrown. The outer member R^2 is bent to lie over the periphery of the wheel N and be out of engagement therewith, and this end carries a spring-actuated pawl r' , which engages with the periphery of the wheel O. The lever R is also provided with a spring, as shown in Fig. 2, for drawing the arm or member R^2 down, and when drawn down this member of the lever bears upon the stud to which the spring of the lever R is secured. When either of the pinions 3 or 4, which are mounted on the slotted shaft E, so as to turn thereon, is in engagement with its clutch, said clutches being thrown in engagement by the movement of the bar K, the vertically-slotted shaft 6 will be turned to actuate the pinion 7, which is geared to the worm-shaft 8, and upon this worm-shaft, which extends horizontally parallel with the brush-frame, in which it bears, is a sleeve 9, which engages with the spiral groove of said shaft, and keyed to this sleeve 9 and carried thereby is a beveled pinion 10, which meshes with a pinion 11, mounted on the center shaft of the brush-carriage, this shaft also carrying a cog-wheel 12, which meshes with a rack-bar C' on the horizontal brush-carrying frame. The center shaft of the brush-carriage is suitably mounted in bearings, which are connected to said carriage C', which travels in the grooves c^2 , formed in the beams C C of the brush-frame. An angular plate W extends from one of the side pieces of the carriage C' over the rack-bar, and is provided with an arm which embraces the

beveled pinion 10, and also with an arm forming a bearing for the center shaft of the brushes.

The brushes S and S', Figs. 1, 2, and 9, are mounted on a rocking frame and pivoted to the center shaft, and these brushes are geared to the cog-wheel on the center-shaft by means of pinions, as shown in Fig. 2, so as to rotate in unison without interfering with the rocking motion of the brush-carriage. The paint is supplied to the center brush through a flexible pipe or hose, which extends to a suitable reservoir, and this pipe is connected to a valved bulb t, Figs. 10 and 11, which is also connected to a pipe T, which lies over the center brush S', and is perforated adjacent thereto. The center shaft of the brush-carriage is provided with a cam T', which is adapted to engage with a wheel on the end of a reciprocating shaft t', which is mounted in suitable bearings secured to the brush-carriage, so that said shaft will be caused to reciprocate and press upon the bulb to force the paint out of the perforated pipe T upon the center brush, from which it is distributed to the other brushes. This shaft t' is encircled by a spiral spring, which holds the same normally in contact with the cam, and it is also provided with a projecting arm t², Figs. 9, 10, and 11, by means of which it can be raised out of contact with the cam, as desired, by simply pulling it away from the cam against the power exerted by the spring and acting on the reservoir to expel such paint as may be in the same, but cutting off further supply by forcing the upper valve to its seat. The bearing-plate by which the shaft t' is secured to the frame can be adjusted thereon so as to give the proper bearing or stroke to the reciprocating shaft.

To the brush-carriage C⁶ are secured pivoted arms U U, provided with rollers u u at their ends, and with wedge-shaped portions u', which are adapted to engage with a sliding bar U'. These curved bars are held normally against the surface of the building by spiral springs attached to the arms and to the boxes in which the bar U' moves, and this sliding bar U' is operated by a lever V. This lever V, which has a member v, is pivoted to the brush-carriage, and the end bears upon a cam d², attached to the center shaft, so that when the movement of the carriage is changed or reversed the cam will throw the member v' of the lever, which bears upon the cam, either up or down, so that the member v will throw the sliding bar U' and raise one of the curved arms, while the opposite arm is permitted to come in contact with the surface of the building.

When there is a depression in the building, as a window-frame, one of the ends will move in said depression, and the end coming in contact with the projection t² will raise the reciprocating arm t' out of engagement with the cam T, so that said reciprocating arm will not force the paint out of the perforated tube

t, except to the extent previously mentioned. Every time the brush-carriage changes the direction of its movement this carriage is tilted and the rotary brushes engage with each other, so that the paint placed upon the center brush is distributed to the end brushes, and the paint deposited by the center brush is smoothed and laid even by the brush following it.

In practice the operation of my invention is as follows: The posts A and cross-beams A' of the main frame are adjusted slightly greater than the height and width of the surface to be painted. The clamps upon the cross-beams A' are then adjusted and secured to the edge of the building, as previously stated, by causing the padded portions a² to bear against the side portions of the building adjacent to its front, so as to maintain the apparatus in a vertical position, and the paint-reservoir is secured to the upper cross-beam A' or other desirable point. The arm m, which extends over the disk M, is placed by raising the hollow knob in one of the desired perforations, and the adjustment of this arm governs the transverse travel of the brush carriage and brushes, this arm engaging with the trip bar or lever so as to advance the intermittent toothed wheel O, to which the cam O' is attached, at the proper time. When the parts are so organized that the pinion 3 is in gear with the beveled wheel f, the shaft E is rotated and the vertical grooved shaft 6 will be turned to rotate the spirally-grooved shaft 8, which will cause the brush-carriage to be moved between the bars C C of the brush-carrying frame. When the brush-carriage reaches near the limit of its movement, the arm m will engage with the lever R and will raise the same to advance the member R² thereof, which carries the pawl and throws the wheel O in engagement with the worm, and as this wheel is turned it will by reason of the studs o and o' engage with the projection n' of the wheel N and advance said wheel. The cam O', engaging with the projections k³ and k⁴ on the bar K, will move the bar so as to carry the clutch h⁷ out of engagement with the pinion 3 and throw the clutch h⁸ in engagement with the pinion 4. This changes the direction of the travel of the carriage without changing the direction of the rotation of the driving-shaft E. When the bar E is thus moved and the shaft rotated, the gear-wheels M, N, and O will be in engagement with the worm, and as the wheel N turns, the projection n² on the face thereof will come in contact with the horizontal bent end of the arm I, which is attached to the plate H, so as to throw said bar out of engagement and throw the clutches g and g' out of engagement with the pinions 1 and 2 to prevent the rotation and upward travel of the brush-carrying frame. These clutches are thrown into engagement with the aforesaid pinions by a spring h², and said clutches can be held permanently out of engagement by throwing the

lever *i* upwardly. The wheel *N* is rotated at the proper time by the studs *o* and *o'* coming in contact with the projection *n'*.

The understanding of the operation of the device will be simplified by bearing in mind that the movable bar *K* operates the clutches which mesh with the pinions for turning the grooved shaft *6*, from which the brush-carriage is caused to travel, and this bar *K*, by means of the V-shaped slot, also governs the lever *P*, which advances the wheel *M*, which engages with the worm. The bar *G* and its continuation, moving on plate *H*, operate the clutches which engage the pinions *1* and *2* for turning the screw-threaded rods by which the brush-carrying frame which supports the brush-carriage is raised or lowered. When it is desired to raise the carriage the lever *i* can be raised to draw the bar to one side and hold the clutches permanently out of engagement.

When the device is in operation and the lever placed as shown in Figs. 1 and 4, the same will operate automatically, first causing the brushes to move across the building, and, after the brush-carriage has reached its limit of movement, the bar *G* will move automatically to throw the clutches in engagement with the pinions *1* and *2*, and the brush-carriage will be raised to a height equal to the length of the brushes, the clutches will then be thrown out of engagement and the brush-carriage will be caused to travel again across the building by the reverse movement of shaft *6*. This operation may be continued until the top of the frame is reached.

When it is desired to operate the brushes independently, the dog *e*², which secures the worm *E'* to the grooved shaft *E*, may be thrown out of engagement with the groove *e*. The brushes can then be operated to move either backward or forward; or by operating the lever *I* the screw-threaded rods *D* may be turned to raise or lower the brush-carrying frame.

The operation of the rotary brushes will be clear from the foregoing description, reference being had to the accompanying drawings.

50 I claim—

1. In a painting-machine, the combination, with a vertical main frame comprising vertical posts and horizontal beams adjustably connected, as described, of clamps for securing the main frame to a building, a transverse brush-carrying frame, a brush-carriage movable horizontally therein, and devices and connections for intermittently vertically moving the brush-carrying frame and horizontally reciprocating the brush-carriage therein, substantially as set forth.

2. In a painting-machine, the combination, with a suitable supporting-frame having a transverse brush-carrying frame provided with a horizontal rack-bar, of a brush-carriage movable in said transverse frame and having brushes geared together, one of which meshes

with the rack-bar, together with devices and connections for reciprocating the brush-carriage in the transverse frame and coincidently 70 revolving the brushes through the medium of the pinion and rack for engagement aforesaid, substantially as set forth.

3. In a painting-machine, the combination, with a main frame having a brush-carrying frame provided with a rack, of a brush-carriage movable in said carrying-frame and provided with a series of vertical brush-shafts geared together, one of said shafts having a pinion engaging with the said rack-bar, and an additional pinion *11*, a spirally-grooved horizontal shaft *f*, having a traveling pinion meshing with said pinion *11*, and a vertical shaft *6*, driving shaft *8*, together with devices for securing the movement of said shaft *6*, substantially as set forth.

4. In a painting-machine, the combination of a vertically-adjustable shifting-frame mounted in suitable supports and provided with a rack-bar, and a center shaft for said frame, upon which a brush is mounted, said shaft carrying a pinion engaging with said rack-bar, whereby the brush-carriage is reciprocated and the brushes rotated, substantially as set forth.

5. The combination, with the main frame consisting, essentially, of posts *A* and cross-beams *A'*, of the clamps *a*, secured to the upper and lower cross-beams, said clamps being provided with projections *a*², screw-threaded 100 crank-shafts *a*⁴, and rods *a*³, whereby the main frame can be connected to the side of a building and adjusted thereon, substantially as set forth.

6. The combination, in a painting-machine, 105 of a vertically-adjustable brush-carrying frame consisting of horizontal beams *C*, and plates *C*⁵, adjustably secured to the beams *C*₂, and provided with outwardly-projecting internally-screw-threaded brackets *c*⁶, with which 110 screw-threaded shafts engage for raising and lowering the frame, substantially as set forth.

7. The combination, in a painting-machine, of the brush-carrying frame comprising beams *C*₂, suitably supported and provided with 115 longitudinal grooves or recesses *c*², a rack-bar *C'*, secured to one of the beams *C*, a brush-carriage provided with flanges which enter the recesses *c*², a brush-carrying frame pivoted on the main shaft of the guide-frame, 120 said shaft having a pinion for operating the brushes, a smaller pinion meshing with the rack-bar, and a beveled pinion through which motion is imparted from the driving mechanism, the parts being organized substantially 125 as shown, and for the purpose set forth.

8. In a painting-machine, a vertically-adjustable frame, a movable brush-carrying frame carried therein, rotary brushes supported by said brush-frame, a spirally-grooved 130 shaft mounted in bearings carried by the vertically-adjustable frame, and a series of pinions geared to each other for turning the spirally-grooved shaft, the bearings for said

pinions being carried by the upper beam C of the vertically-adjustable frame, substantially as set forth.

9. The combination, in a painting-machine, of a longitudinally-grooved shaft 6 and screw-threaded shafts D D, a brush-carrying frame connected to said shafts, said shafts being provided at their lower ends with pinions, a horizontal shaft E, carrying pinions 1, 2, 3, and 4, and a clutch for throwing said pinions in and out of gear with the pinions of the vertical shafts D D and 6, so that when the horizontal shaft E is rotated the brush-carrying frame may be either reciprocated or raised and lowered, substantially as set forth.

10. The combination, with the vertically-moving brush-carrying frame and reciprocating brush-carriage thereon, of adjacent parts and connections, threaded shafts and longitudinally-grooved shaft 6, each provided at the end with beveled pinion, a horizontal shaft E, beveled pinions loosely mounted on said shaft to mesh with the pinions of shafts D and 6, a sliding bar provided with clutches to lock the loose pinions to shaft E, and a lever and link to shift said bar, substantially as set forth.

11. The combination, in a painting-machine, of a vertical shaft 6, having a longitudinal groove, a worm-shaft f, gearing connecting said shafts, a reciprocating brush-carriage, operating means for connecting said carriage with the worm-shaft, the shaft E, having pinions journaled thereon, and clutches connected to a bar K for throwing said clutches in and out of engagement with the pinions 3 and 4, substantially as set forth.

12. The combination, substantially as described, of the main frame, the horizontal brush-carrying frame vertically adjustable thereon, a brush-carriage carrying a series of rotary brushes geared together, and means connected with one of the brush-shafts for moving the brush-carriage along the horizontal brush-carrying frame when said brush-shaft is revolved, substantially as set forth.

13. In a painting-machine, the combination of the main frame, a vertically-moving brush-carrying frame mounted thereon, a brush-carriage supported by said vertically-moving frame, and the vertical screw-shafts controlling the movement of the vertically-moving frame and in turn operated by automatically-reversing mechanism, substantially as set forth.

14. The combination, substantially as described, of the main frame, the horizontal frame, a brush-carriage supported by said horizontal frame, a brush-frame pivoted centrally to said carriage, and means connected with the brush-carriage for rotating the brushes as the carriage is moved upon the horizontal frame, substantially as set forth.

15. The combination, substantially as described, of the brush-carrying frame and its brushes, the paint-tube having a flexible sec-

tion, the sliding rod t', and the spring-pressed arms U, pivoted on the brush-carrying frame.

16. In a painting-machine, the combination, with the central brush-shaft, of a cam T' mounted thereon, an adjustable plate having bearings for a sliding rod, sliding rod t', having a spiral spring and a roller at one end engaging the cam and an enlargement at the opposite end, and a bulb having a valve 75 therein and situated in the paint-feeding tube, said enlarged end of rod t' bearing against the bulb and regulating the feed through the tube by compression, substantially as set forth.

17. In a painting-machine, the combination, with the brush-carrying frame and a brush-carriage, of the arm V, having an angular extension v, the arms U, having rollers in their outer ends and springs attached thereto and to the elevating-frame, and also having enlarged parts u', the sliding rod t', cam T' in the upper end of the central brush-shaft, and the bulb t in the feed-pipe, substantially as set forth.

18. In a painting-machine, the combination of the main frame, vertically-adjustable brush-carrying frame, the vertical screw-shafts D D, spiral-grooved shaft or rod 8 and plain vertical shaft 6, the shaft E, having worm E', the index-wheel M, wheel O, cam O', having a 95 spiral arm, wheel N, having lug n², stop-arm I, the arm R², carrying pawl r', the arm R', the pivoted arm P, carrying pawl p', and the bar K, substantially as set forth.

19. The combination, substantially as described, of the vertical screw-shafts provided with pinions, the power-shafts having loose pinions and clutches, the horizontal frame, and a shifting-bar to control the position of the clutches on the power-shaft.

20. The combination, substantially as described, of the horizontal brush-carrying frame and the screw-shafts, and grooved shaft provided with pinions, the power-shaft provided with loose pinions and clutches, a shifting-bar connected to the clutches which control the screw-shafts, and a slide-bar connected to the clutches which control the movement of the grooved shaft.

21. The combination, substantially as described, of the horizontal brush-carrying frame, the brush-carriage, the screw-shafts and grooved shaft provided with pinions, the power-shaft having loose pinions, a worm and clutches, a shifting-bar G, connected to the clutches which control the screw-shafts, a slide-bar K, connected to the clutches which control the grooved shaft, and mechanism actuated by the worm on the power-shaft to automatically shift said bars.

22. The combination, substantially as described, of the horizontal frame, the brush-carriage, the screw-shafts and grooved shaft provided with pinions, the power-shaft having loose pinions, a worm and clutches, a slide-bar K, connected to the clutches which control the movement of the grooved shaft,

a spring-pressed shifting-bar G, provided with a dog, and a gear-wheel N, driven by the worm and provided with a cam-block to engage said dog and shift said bar.

5 23. The combination, substantially as described, of the horizontal frame, the brush-carriage, the screw-shafts and grooved shaft provided with pinions, the power-shaft having loose pinions, a worm and clutches, a slide-bar K, connected to the clutches which control the movement of the grooved shaft, a spring-pressed shifting-bar G, provided with a dog, a gear-wheel N, driven by the worm and provided with a cam-block to engage the dog and shift said bar, and a lever and link to hold the dog free from the path of the cam-block.

24. The combination, substantially as described, of the horizontal brush - carrying frame, the brush-carriage, the screw-shafts and grooved shaft provided with pinions, the power-shaft having loose pinions, a worm and clutches, a shifting-bar G, connected to the clutches which control the screw-shafts, a 25 slide-bar K, connected to the clutches which control the movement of the grooved shaft and provided on its rear face with lugs, means for moving the shifting-bar, and a gear-wheel O, driven by the worm and provided with a

cam-shaped hub to engage the lugs on the 30 slide-bar.

25. The combination, substantially as described, of the horizontal frame, the brush-carriage, the screw-shafts and grooved shaft provided with pinions, the power-shaft having loose pinions, a worm and clutches, a shifting-bar G, connected to the clutches which control the movement of the grooved shaft and provided on its rear face with lugs, a mutilated gear-wheel M, mounted above and 35 driven by the worm, an adjustable stud m' carried thereby, the mutilated gears N and O, constructed as described, mounted below and driven by the worm, a spring-pressed lever R, one end of which is arranged in the 40 path of the stud m', the other end being provided with a spring-pawl to engage the gear O, and an elbow-lever P, provided at one end with a pawl to engage wheel M and at the other end with a pin engaging a V-shaped 45 slot in the slide-bar.

In testimony whereof I affix my signature in presence of two witnesses.

ENOS S. HAWKS.
